UNITED STATES PATENT OFFICE.

ANGELUS E. GLISTRIDIS, OF NEW YORK, N. Y.

DESIGN FOR A CANDLE.

Application filed October 9, 1922. Serial No. 3,918. Term of patent 14 years.

To all whom it may concern:

Be it known that I, ANGELUS E. GLISTRIDIS, a subject of the King of Greece, and a resident of the city of New York, borough of Manhattan, in the county and State of New York, have invented a new, original, and ornamental Design for Candles, of which the following is a specification, reference being had to the accompanying drawings, forming a part thereof.

Figure 1 is a side elevation of a candle, showing my new design; and

Figure 2 is a horizontal section of the candle.

I claim:

The ornamental design for a candle as shown.

ANGELUS E. GLISTRIDIS.
